UNITED STATES PATENT OFFICE.

PHILLIP BIRCH, OF ERIE, PENNSYLVANIA.

GROOVING AND SEAMING MACHINE.

SPECIFICATION forming part of Letters Patent No. 340,413, dated April 20, 1886.

Application filed March 4, 1886. Serial No. 194,048. (No model.)

To all whom it may concern:

Be it known that I, PHILLIP BIRCH, a citizen of the United States, residing at Erie, in the county of Erie and State of Pennsylvania, 5 have invented certain new and useful Improvements in Grooving and Seam-Setting-Down Machines; and I do hereby declare the following to be a full, clear, and exact description of the invention, such as will enable others 10 skilled in the art to which it appertains to make and use the same, reference being had to the accompanying drawings, and to the letters of reference marked thereon, forming part of this specification.

15 My invention relates to grooving and seam-setting-down machines; and it consists in the improvements hereinafter set forth and explained.

20 My invention is illustrated in the accompanying drawings, in which Figure 1 is a perspective view of my improved grooving and seam-setting-down machine. Fig. 2 is a perspective view of a section of the improved stake or mandrel used in my improved machine. Fig. 3 is a side elevation of a hand 25 groove and seam-setting-down machine embodying my improved stake or mandrel.

Like letters refer to like parts in all the figures.

30 In the construction of my improved grooving and seam-setting-down machine, A A' are the legs or upright portion of the frame. The upper part of the frame A is provided with a cross-piece, B, having ears or bearings C C, 35 in which the hammer D is pivoted, as herein-after described. The cross-piece B also projects beyond the upright frame A on one side at E, where it is secured to the frame-work F F, which serves to connect the uprights A A' 40 together. On the top of the upright frame A', and parallel to the cross-piece B, there is secured, by being preferably cast as a part of A', a tubular bearing or sleeve, G, this tubular bearing or sleeve G being securely attached 45 to the frame-work F F, which, together with the uprights A A', form the frame-work of the machine.

The hammer D is mounted in the bearings C C on the cross-piece B, preferably by means 50 of a rod, H, passing through the ends d d of the frame of the hammer D, and also through the bearings C C. Upon the rod H is placed

a spiral retracting-spring, I, adapted to raise the hammer, after a blow is struck, into position for the next stroke.

55 The hammer D is operated to produce a stroke by a treadle, J, which is mounted in bearings in the lower part of the upright frame A, and connected to the arms d d of the hammer D by connecting-rods K K, so that the operator can bring down the hammer D upon the stake or mandrel L, producing a sharp blow thereon. This stake or mandrel L is constructed of a round bar of metal, and may be of any convenient diameter to suit the 60 class of work upon which the machine is at the time employed, one end of the stake or mandrel L fitting into the bearing or sleeve G, where it is secured by means of a set-screw, 65 g, and any number or sized mandrels may be 70 used in the machine, the ends fitting into the bearing G being made of equal size. This stake or mandrel L is provided with one or more longitudinal grooves N. One of the edges, n, of these grooves N is fixed and stationary, while the other edge of the groove N is in the form of a movable guide, O, which is 75 set in a longitudinal recess in the stake or mandrel L upon springs o, its upward movement being limited by the size of the slots o', 80 so that when it is up it, together with the fixed edge n, forms the groove N. When, however, a sheet-metal seam is placed in the groove N, and the hammer D brought down upon the stake or mandrel L, the movable side 85 or guide O on one side of the groove N is forced downward by the force of the blow, and at the same time the metal projecting over the fixed edge n of the groove N is crimped down 90 so that the sheet is grooved throughout its entire length on that side, and at the same time the blow of the hammer D sets the seam together and finishes it, the seam thus formed being entirely below the upper surface of the metal. For example, in a stove, conductor, 95 or other pipe the outside is left smooth and even, the entire fold of the seam being on the inside of the pipe.

In one end of the face of the hammer D, I place a punch, Q, which, when the hammer D 100 is struck down upon the stake or mandrel L, enters a hole, Q', in the face of the groove N, so that in grooving and setting down the seams in stove-pipes and other pipes which it is de-

sired to rivet a hole may be punched through the folds forming the seam, if desired. However, this part of my device may be dispensed with, if desired, as rivets are not necessary or used at all in many of the kinds of pipe which are adapted to be grooved and seamed in my machine. This stake or mandrel L may have grooves of different widths on opposite sides thereof, and both the mandrel L and face of the hammer D may be made of any convenient length to take on cylinders of all the lengths ordinarily made of sheet metal or tin, both grooving and setting down the seam, so as to completely finish it at one operation, which consists of one or more blows of the hammer D, according to the thickness of the metal being so grooved and set down.

In Fig. 3 I have shown my improved stake or mandrel L in combination with an ordinary hand grooving and seaming machine. The roller P in this machine in traveling along the groove N depresses the movable side or guide O, producing a similar result to that produced by the hammer D. (Shown in Fig. 1.)

Having thus described my improved grooving and seam-setting-down machine, I do not claim, broadly, the combination of a hammer striking down upon a groove in a table or other flat surface, which operates to groove the metal; but I am not aware of any such construction adapted to both groove and set down the seam at one operation, as I do.

Therefore what I claim as new, and desire to secure by Letters Patent of the United States, is—

1. The combination, in a grooving and seam-setting-down machine, of a stake or mandrel mounted in the frame of the machine and provided with one or more longitudinal grooves therein, one of the edges of which grooves is movable, with a hammer mounted in the frame of the machine adapted to strike downward upon said stake or mandrel, substantially as and for the purpose set forth.

2. In a grooving and seam-setting-down machine, a stake or mandrel having one or more longitudinal grooves therein, one of the edges of which grooves is movable, substantially as and for the purpose set forth.

3. The combination, in a grooving and seam-setting-down machine, of standards connected together at one end thereof by a cross-frame,

a pivoted hammer provided with retracting-springs, and treadle mechanism for operating the same mounted in said frame, with a sleeve 55 on one of said frames adapted to receive and support the stake or mandrel upon which said hammer strikes, substantially as and for the purpose set forth.

4. The combination, in a grooving and seam-setting-down machine, of a removable stake or mandrel having longitudinal grooves therein, with a tubular sleeve or bearing on the frame of said machine adapted to support said removable stake or mandrel under the face of 65 the hammer of said machine, substantially as and for the purpose set forth.

5. The combination, in a grooving and seam-setting-down machine, of a pivoted hammer mounted in the frame of said machine, having 70 a rivet-punch in the face thereof, with a removable stake or mandrel mounted in a sleeve or bearing on said frame, and having therein one or more longitudinal grooves, one of the sides of which grooves is movable, and having 75 openings in the face of the groove for the entry of the punch in the face of the hammer, substantially as and for the purpose set forth.

6. The combination, in a stake for grooving and seam-setting-down machines, of longitudinal grooves N, having the fixed edge n, with the movable edge or guide O, resting upon the springs o, and adapted to be forced downward during the setting down of the seam, substantially as set forth.

7. The combination, in a grooving and seam-setting-down machine, of the upright frames A A', and cross-frame F, the hammer D, provided with the retracting-spring H, mounted in the top of the frame A, and the treadle J, 90 mounted in the lower part of the frame A, and connected with the arms d d of the hammer D by connecting-rods K K, with a tubular bearing or sleeve, G, on the top of the frame A', and the removable stake or mandrel L 95 supported thereby, all substantially as and for the purpose set forth.

In testimony whereof I affix my signature in presence of two witnesses.

PHILLIP BIRCH.
